DANIEL MAPES, OF MAMARONECK, NEW YORK, ASSIGNOR TO WALTER KIDDE & COMPANY, INC., OF NEW YORK, N. Y., A CORPORATION OF NEW YORK

RELEASE DEVICE FOR FLUIDS UNDER PRESSURE

Application filed October 29, 1928. Serial No. 315,648.

The present invention is embodied in an improved releasing device to permit the escape of fluids confined in a container under pressure and is particularly adapted for use in fire extinguishing systems wherein the fire extinguishing medium is maintained under pressure in suitable containers. More specifically, the invention is embodied in a releasing device of this character which is adapted to be operated manually, the improved construction greatly facilitating the manual operation and effecting a more positive actuation of the releasing mechanism.

Where a considerable quantity of a fire extinguishing medium is maintained under a high pressure within a container, the frangible disc necessary to confine the medium is frequently of such character that the rupturing thereof manually is attended with considerable difficulty. Accordingly, the present invention has for an object the provision of a manual means for rupturing such frangible disc and releasing the confined fluid, which will require comparatively little effort for the operation thereof, at the same time permitting the free and unobstructed flow of the medium from the container after the frangible disc has been ruptured.

Further objects of the invention will be apparent as the description proceeds and reference will now be had to the accompanying drawings wherein the single figure is a view in section, taken on a vertical plane passing through the axis of the releasing mechanism and the container.

Referring to the above drawing, *a* designates a container for a fire extinguishing medium which is to be maintained under a considerable pressure therein. Threaded into the neck *a'* of the container is a disc body *b* to which a siphon tube *a''* is secured. This siphon tube extends adjacent the bottom of the container and communicates with an axial passage *b'* within the disc body to permit the discharge of the confined medium when conditions are suitable therefor. A filler check valve *b''* may be carried by the disc body, the specific construction thereof not being essential to the present invention. The disc body *b* is formed with a disc seat *b''* upon which a

frangible disc *c* is seated. A suitable sealing gasket *c'* may be provided and the gasket and disc are held securely against the seat by means of a coupling *d* which is threaded into the upper end of the disc body. This coupling, in turn, is formed with a seat *d'* upon which frangible disc *e* and sealing gasket *e'* are received. A valve bonnet *f* is threaded into the upper end of the coupling *d* to press the disc *e* and gasket *e'* toward the seat *d'*.

Coupling *d* is formed with an axial passage *d''* having a restricted portion *d'''* within which a plunger *g* is received. An enlarged head *g'* is formed on the plunger and is received within an enlarged portion *d''* of the coupling *d*. The plunger is of such length that it will engage both frangible discs when the latter are secured in position, an axial bore *g''* being formed in the plunger to provide a channel between the discs. Additional passages *g'''* are formed in the enlarged portion of the plunger for communication between the coaxial passage *d''* and the space above the enlarged head *g'* of the plunger *g*.

The valve bonnet *f* carries a plunger *h* provided with a striking head *h'* and a pusher head *h''*. The head *h'* rests upon the frangible disc *e* and is formed with an axial passage *h''* and radial passages *h'''*. The passage *h''* is coaxial with respect to the passage *g''*. A discharge aperture *f'* may be threaded to receive a discharge pipe for conducting the medium to a desired location.

The length of the plunger *g* is such that it will support the frangible disc *c* against the pressure of the medium within the container, the plunger in turn being supported by the frangible disc *e* which serves as a reinforcing means. In this manner, the frangible disc *c* may be of considerably thinner material than ordinarily required. When the striking head *h'* is struck with the hand, plunger *g* is forced downwardly to rupture the frangible disc *c*. There is sufficient flexibility in the frangible disc *e* to permit the required advance of the pusher head *h''* and plunger *g* to drive the lower end of the plunger *g* through the frangible disc *c*. The pressure of the fire extinguishing medium is then exerted against the under side of the frangible

disc *e*, shearing it off against the circumference of the internal bore of the bonnet *f*. The pusher head *h*² recedes until it engages the upper extremity of the internal bore of the bonnet, permitting the plunger *g* to rise above the restricted portion which is formed at the lower end of the coupling *d*. This provides a path for the flow of the fire extinguishing medium around the outside of the plunger *g* and through ports *g*³. Although the cut-out portion of the frangible disc *e* is still resting against the under side of the pusher head *h*², the force of the fire extinguishing medium will be sufficient to 15 push back the edge of the frangible disc *e*, permitting the medium to discharge through the outlet *f*².

If the pressure within the container should become excessive at a time when the fire extinguishing system is not in operation, the frangible disc *e* will burst and permit the medium to pass through the passage *g*² and rupture the frangible disc *e*, the medium being discharged through the passages *h*³ and 25 *h*⁴ into the chamber *f*'.

It will be apparent that the reduction in the size of the frangible disc *e* will permit the piercing thereof to be accomplished with comparatively little manual force. The discharge of the medium is free and unobstructed and the structure is such that it may be operated positively and effectively.

While the embodiment of the present invention herein described has been pointed out as particularly applicable to direct manual operation, it will be understood that the device may be operated by any force as by a spring, a weight, or any other means released manually or automatically, and that the 30 present invention is not limited except as defined in the following claims.

I claim as my invention:

1. A releasing mechanism of the character described comprising a container for a fluid under pressure, a frangible disc carried by the container, a reinforcing means, pressure transmitting means between the reinforcing means and the disc, and means to exert a pressure on the transmitting means to rupture the disc against the pressure in the container.

2. A releasing mechanism of the character described comprising a container, a frangible disc carried by the container, a reinforcing means, pressure transmitting means between the reinforcing means and the disc, and means to exert a pressure on the transmitting means through the reinforcing means to rupture the disc.

3. A releasing mechanism of the character described comprising a container for a fluid under pressure, a frangible disc carried by the container, a second disc, pressure transmitting means between the discs, and means to 60 exert a pressure on the first disc through the

transmitting means to rupture said first disc against the pressure in the container.

4. A releasing mechanism of the character described comprising a container for a fluid under pressure, a frangible disc carried by the container, a second disc, pressure transmitting means between the discs, and means to exert a pressure on the first disc through the second disc and transmitting means to rupture the first disc against the pressure in the container.

5. A releasing mechanism of the character described comprising a container for a fluid under pressure, a frangible disc carried by the container, a second frangible disc, a plunger between the discs and spacing the two, and means to exert a pressure on the second disc over the plunger to rupture the first disc against the pressure in the container.

6. A releasing mechanism of the character described comprising a container, a frangible disc carried by the container, a second frangible disc, a plunger between the discs and spacing the two, a passage in the plunger communicating with the first disc, and means to exert a pressure on the second disc over the plunger.

7. A releasing mechanism of the character described comprising a container, a frangible disc carried by the container, a second frangible disc, a plunger between the discs and spacing the two, a passage through the plunger communicating with each disc, and means to exert a pressure on the second disc over the plunger.

8. A releasing mechanism of the character described comprising a container for a fluid under pressure, a frangible disc carried by the container, a coupling carried by the container, an axial passage in the coupling, a second frangible disc carried by the coupling, a plunger in the passage and spacing the two discs, and means to exert a pressure on the second disc over the plunger to rupture the first disc against the pressure in the container.

9. A releasing mechanism of the character described comprising a container for a fluid under pressure, a frangible disc carried by the container, a coupling carried by the container, a second frangible disc carried by the coupling, an axial passage in the coupling between the discs, a plunger in the passage spacing the discs, and means to exert a pressure on the second disc over the plunger to rupture the first disc against the pressure in the container.

10. A releasing mechanism of the character described comprising a container, a frangible disc carried by the container, a coupling carried by the container, a second frangible disc carried by the coupling, an axial passage in the coupling between the discs, a plunger in the passage spacing the discs, a passage in the plunger between the discs, and means to exert a pressure on the second disc over the plunger to rupture the first disc against the pressure in the container.

exert a pressure on the second disc over the plunger.

11. A releasing mechanism of the character described comprising a container, a frangible disc carried by the container, a coupling carried by the container, a second frangible disc carried by the coupling, an axial passage in the coupling between the discs having an enlarged portion, a plunger in the passage of less diameter than the passage, an enlarged portion on the plunger engaging the walls of the enlarged portion of the passage, passages in the enlarged portion of the plunger; an axial passage in the plunger between the discs, and means to exert a pressure on the second disc over the plunger.

12. A releasing mechanism of the character described comprising a container, a frangible disc carried by the container, a coupling carried by the container, a second frangible disc carried by the coupling, a bonnet over the second disc securing the latter in the coupling, a plunger carried by the bonnet and engaging the second disc, an axial passage in the coupling between the discs having an enlarged portion, a second plunger in the passage of less diameter than the passage, an enlarged portion on the second plunger engaging the walls of the enlarged portion of the passage, passages in the enlarged portion of the second plunger, and an axial passage in the second plunger between the discs.

13. A releasing mechanism of the character described comprising a container, a frangible disc carried by the container, a coupling carried by the container, a second frangible disc carried by the coupling, a bonnet over the second disc securing the latter in the coupling, a plunger carried by the bonnet coaxial thereto and engaging the second disc, an axial passage in the plunger communicating with an outlet, an axial passage in the coupling between the discs having an enlarged portion, a second plunger in the passage of less diameter than the passage, an enlarged portion on the second plunger engaging the walls of the enlarged portion of the passage, passages in the enlarged portion of the second plunger, and an axial passage in the second plunger between the discs.

14. A releasing mechanism of the character described comprising a container, a frangible disc carried by the container, a coupling carried by the container, a second frangible disc carried by the coupling, a bonnet over the second disc securing the latter in the coupling, a chamber in the bonnet, an outlet for the chamber, a plunger carried by the bonnet and engaging the second disc, said plunger being coaxial with respect to the bonnet, an axial passage in the plunger, passages in the plunger between the axial passage therein and the chamber, an axial passage in the coupling between the discs having an enlarged portion, a second plunger in the

passage of less diameter than the passage, an enlarged portion on the second plunger engaging the walls of the enlarged portion of the passage, passages in the enlarged portion of the second plunger, and an axial passage in the second plunger between the discs.

15. A releasing mechanism of the character described comprising a container, a frangible disc carried by the container, a coupling carried by the container, a second frangible disc carried by the coupling, a bonnet over the second disc securing the latter in the coupling, a chamber in the bonnet, an outlet for the chamber, a plunger carried by the bonnet and engaging the second disc, said plunger being coaxial with respect to the bonnet, an axial passage in the plunger, passages in the plunger between the axial passage therein and the chamber, an axial passage in the coupling between the discs having an enlarged portion, a second plunger in the passage of less diameter than the passage, an enlarged portion on the second plunger engaging the walls of the enlarged portion of the passage, passages in the enlarged portion of the second plunger, and an axial passage in the second plunger between the discs, and means to exert a force on the first plunger.

This specification signed this 11th day of October, A. D. 1928.
